UNITED STATES PATENT OFFICE.

JOHN WALKER INGLESBY, OF NEWPORT NEWS, VIRGINIA.

STENCILING MACHINE.

Application filed October 5, 1925. Serial No. 60,548.

This invention relates to stenciling machines of that type adapted to be pushed, like a plane, over the surface to be stenciled so as to leave the stencil print upon said 5 surface.

It is an object of the present invention to provide simple and efficient means for connecting the stencil to drums forming a part of the machine, means being employed for 10 resetting the stencil automatically after each impression or stencil print has been made.

A further object is to provide a means for gradually retarding the relative movement of the stencil and the machine both 15 during the resetting of the stencil, thereby to relieve the machine of the wear and tear that might result from the abrupt stopping of the movable parts.

A further object is to provide a brush 20 for use in connection with the stencil, means being employed for rotating said brush solely during the forward movement or stenciling strokes of the machine.

A still further object is to provide a brush 25 of the fountain type having means constantly under the control of the user whereby the flow of ink to the bristles of the brush can be regulated.

A still further object is to provide a machine 30 of this character the parts of which can be assembled readily.

With the foregoing and other objects in view which will appear as the description proceeds, the invention resides in the combination and arrangement of parts and in the details of construction hereinafter described and claimed, it being understood that changes in the precise embodiment of the invention herein disclosed may be made 40 within the scope of what is claimed without departing from the spirit of the invention.

In the accompanying drawings, the preferred form of the invention has been shown.

In said drawings, 45 Figure 1 is a vertical longitudinal section through one side portion of the housing of the machine, the interior mechanism being shown in elevation.

Figure 2 is a section on line 2—2 Figure 1.

Figure 3 is a section on line 3—3 Figure 1.

Figure 4 is a section on line 4—4 Figure 1.

Figure 5 is a central vertical longitudinal section through the machine. 55

Figure 6 is a plan view.

Figure 7 is an enlarged section on line 7—7 Figure 3.

Figure 8 is a perspective view of a portion 60 of one of the tops of the drum, showing one of the brake or retarding members.

Figure 9 is a perspective view of the cam 65 constituting the other brake or retarding member.

Figure 10 is a section on line 10—10 Figure 2.

Figure 11 is a section through one of the drums showing the gripping roll in released 70 position.

Referring to the figures by characters of reference 1 designates a skeleton frame which carries the mechanism of the machine. This skeleton frame includes an intermediate cross bar 2 and oppositely extending side 75 arms 3 and 4. Journaled in the front arms 3 are the reduced ends 5 of a tubular shaft 6. The skeleton frame 1 fits snugly within a housing 7 and this housing is connected to the skeleton frame by a rod 8 extended longitudinally through tubular shaft 6 and through apertures in opposed sides of the housing. The rod may be held detachably 80 in position by nuts 9 engaging the ends thereof. Thus the tubular shaft is held assembled with the skeleton frame and said frame is held assembled with the housing. 85

Mounted on the end portions of the tubular shaft 6 are the circular heads 10 and 11 of the front drum of the machine. Each of 90 these heads has a boss 12 extending outwardly therefrom to abut against the adjacent arm 3 and hold the heads properly spaced from the skeleton frame.

The casing of the drum is substantially 95 cylindrical as shown at 13 and is fitted between the heads 10 and 11, there being circular depressions in the inner faces of the heads to receive the ends of the casing. The outer surface of the casing 13 is formed with a covering 15 of felt or the like. Located in that portion of the drum casing which is normally lowermost, is a longitudinal depression or groove 16. Arranged within this groove is a clamping or gripping roll 100 17 having alining bearing pins 18 eccentrically mounted at the ends thereof and journaled within the heads 10 and 11. One

- of these pins is formed with a crank arm 19 whereby the roll can be rotated to move into or out of gripping position relative to the wall of the groove 16.
- 5 Arranged upon the inner surface of the head 11 is a retarding cam 20 a portion of the inner or active face of which is disposed in a plane extending obliquely across the tubular shaft 6. A stop lug 21 is extended 10 inwardly from the inclined face of the cam 20 at the peak thereof, which terminates in a shoulder 20' extending the height of the cam. This is clearly shown in Figure 8 of the drawing.
- 15 Formed longitudinally within the tubular shaft 6 is a groove 22 and slidably mounted on this grooved portion of the shaft 6 is a sleeve 23 having a tapered key 24 extending from one end thereof and slidable within 20 the groove 22. A spring 25 on the shaft 6 bears at one end against sleeve 23 and at its other end against a collar 26 secured to shaft 6. This spring serves to hold the sleeve 23 normally in position with its key 25 24 pressing against the inclined face of cam 20. The key 24 is of a width considerably less than the width of the groove 22 so that a lost motion connection is provided between sleeve 23 and shaft 6 when said parts are 30 rotated in one direction. This is for the purpose hereinafter pointed out. The parts of the front drum in which this retarding mechanism is housed are held assembled by longitudinal bolts 27 engaging the heads 10 and 11 at desired intervals.
- The rear drum of the machine which is located between the rear arms 4 includes heads 28 and 29 mounted for rotation on a tubular shaft 30. This shaft has reduced 40 ends 31 seated in the arms 4 and a rod 32 is extended through the shaft and through openings 33 formed in the housing 7 thereby to hold the parts assembled. The ends of this rod are provided with nuts 34 or the like for holding the rod in place. Each head 28 and 29 has a laterally extending boss 35 designed to bear against one of the arms 4 to hold the heads properly spaced therefrom. The casing 36 of the drum is seated 45 in the inner faces of the head and these heads and the casing are held assembled by tie rods 37. A longitudinal groove or depression 38 is formed in that portion of the drum casing which is normally lowermost, 50 as shown at 38, and a felt covering 39 is mounted on the casing 36. A clamping or gripping roll 40 is extended longitudinally within the groove or depression 38 and has eccentrically arranged aligning bearing pins 55 41 at the ends thereof journaled within the respective heads 28 and 29. One of these pins is formed with a crank arm 42 whereby the roll can be revolved for the purpose of moving it into or out of gripping position.
- 60 Secured to the tubular shaft 30 are spaced disks 43 between which is arranged a spiral spring 44. One end of this spring is secured to the tubular shaft 30 as shown in Figure 5 while the other end is fastened preferably to one of the tie rods 37. The spring is so 70 coiled that when the drum is rotated during the forward or stenciling movement of the machine said spring will be placed under tension.
- The cross bar 2 of the skeleton frame 1 75 is provided, between its ends, with a bushing 45 in which is journaled a tubular shank 46 extending upwardly from the central portion of the top plate 47 of a fountain brush. The body of this brush, which is 80 cylindrical, has been indicated at 48 and is divided by a partition 49 into an upper compartment or reservoir 50 and a lower or distributing compartment 51. Partition 49 is inclined downwardly toward an opening 52 preferably located at the center thereof. A bottom plate 53 engages the lower end of the body 48 and has brush bristles 54 connected thereto in any manner desired and extending downwardly therefrom. Apertures 55 are formed in this bottom plate so that when ink is directed into the distributing compartment 51 it will be free to spread therein and flow downwardly through the different apertures 55 to the bristles. 95 The parts of the brush are held assembled by tie bolts 56 extending therethrough as shown.
- The tubular shank 46 is formed with an annular shoulder 57 constituting an abutment for one end of a coiled spring 58 the other end of which bears against a beveled gear 59. This gear is mounted to rotate with the shank 46 but has a feathered connection therewith as shown at 60 whereby 10 the shank is free to slide longitudinally within the gear. Said gear is journaled within a bushing 61 seated in the top portion of the frame 1 and insertable upwardly through an opening 62 in the top portion of 11 the housing 7. A nut 63 can engage the outer end portion of the bushing for holding the same assembled with the skeleton frame and with the housing. Obviously spring 58 exerts a constant downward thrust against the shoulder 57 so as to cause the bristles 12 of the brush to press firmly against a stencil located thereunder as hereinafter explained.
- The upper end portion of the shank 46 is 12 screw threaded exteriorly as shown at 64 so as to engage a collar 65 which is adjustable longitudinally thereof by screwing or unscrewing the same and is thereafter held against adjustment by a set screw 66. The periphery of this collar is knurled or grooved for engagement by a spring pin 67 extending downwardly from the knurled lower end portion 68 of a cup 69. This cup 13 is screwed onto and carried by the exte-

riorly screw threaded upper end portion of a tubular spindle 70 in threaded engagement with the inner wall of the shank 46. The lower end of the spindle is tapered to 5 constitute a valve 71 adapted to fit snugly within and to close the opening 52 in partition 49. This spindle has its lower portion of less diameter than its upper or threaded portion and apertures 72 are provided with 10 in the wall of the spindle close to the threaded portion thereof for the purpose of establishing communication between the interior of said spindle and the interior of the shank 46. Additional apertures 73 are provided 15 within the wall of the spindle close to the closed tapered end 71 thereof and constitute means for establishing communication between the interior of the spindle and the reservoir 50.

20 The connection between the cup 69 and the spindle 70 is sufficiently tight to insure rotation of the spindle with the cup when said cup is turned by the operator. Thus the spindle can be adjusted longitudinally to 25 open or close the aperture 52.

A cap 74 having a hollow cylindrical extension 75 is screwed into the cup 69 and has a central opening 76. The lower end of this extension 75 is closed by a disk 77 provided 30 with small apertures 78. A plunger 79 projects through the aperture 76 and has a tapered intermediate portion 80 adapted to bear against the wall of the aperture 76 and serve as a valve for closing the aperture. 35 A recess 81 is provided in the lower end of the plunger and seated therein is a spring 82 which bears downwardly against the disk 77. This spring serves to hold the tapered portion of the plunger normally pressed 40 yieldingly against the wall of the aperture 76. Small apertures 83 extend through the tapered portion of the plunger at points below the points of contact with the wall of aperture 76, these apertures 83 constituting 45 means for setting up communication between the upper end of the recess 81 and the interior of the cylindrical extension 75. Grooves 84 are extended longitudinally 50 within the outer surface of the plunger 79 below the tapered portion 80 and communicate with radial end grooves 85 in the lower end of the plunger. Thus air is at all times free to circulate through and longitudinally along the outside of that portion of the 55 plunger housed within the extension 75. Normally, however, the admission of air through aperture 76 to the interior of the spindle 70 is prevented by the tapered portion 80 of the plunger bearing against the wall of the aperture 76. Only when plunger 60 79 is depressed, will air flow into the upper end of the spindle.

A shaft 86 is journaled within the skeleton frame and extended at right angles to the shank 46. A beveled gear 87 is secured

to this shaft and constantly meshes with the gear 59. A gear 88 is loosely mounted on shaft 86 and has a ratchet face 89 normally engaged by a clutch member 90 which is rotatable with but slidably on the shaft 86. 70 This connection between the clutch member 90 and shaft 86 is effected by the use of a pin 91 extending diametrically through the clutch member and through a slot 92 within the shaft. A spring 93 bears against one 75 end of the clutch member so as to hold the same normally in engagement with the ratchet face 89. These cooperating portions are so shaped and located that when gear 88 is rotated in one direction motion will also 80 be transmitted to the shaft 86. However, when gear 88 is rotated in the opposite direction the shaft 86 will remain stationary.

Gear 88 receives motion from a larger gear 94 journaled on one side portion of the skeleton frame and intermediate gears 95 mesh with this gear 94. One of the intermediate gears also meshes with a gear 96 secured to the head 11 of the front drum of the machine. The other gear 95 meshes with a gear 97 secured to the head 29 of the rear drum. 90

An arcuate guide plate 98 is secured within the front portion of the housing 7 and extends over the front drum of the machine. A knob 99 may be attached to the front 95 portion of the top of the housing and a handle or grip 100 can be connected to and extended upwardly from the rear portion of the top of the housing.

For the purpose of counting the number 100 of stenciling operations an ordinary counter indicated generally at 101 is located on the housing. This counter has the usual operating lever 102 and in the present instance this lever is engaged by the slotted end of a 105 tripping lever 103 held normally in a predetermined position by a spring 104. The other end of lever 103 is adapted to be engaged by one of the pins 18 once during each complete rotation of the drum carrying 110 the same.

In using this machine a stencil indicated generally at S is inserted at one end between the front drum and the arcuate guide 115 98 so as to completely encircle said drum. Said end of the stencil is placed within the groove 16 after which the roll 17 is rotated by means of the crank arm 19 so as to cause it to grip upon the end of the stencil as shown in Figure 5. The remainder of the stencil is then carried under the bristles of the brush and inserted at its rear end in the groove 38 of the rear drum. Roll 40 is then rotated to grip said end. Cap 74 is removed from the cup 69 and a suitable free running ink or other marking fluid is poured into the cup and will flow downwardly through the spindle 70 to the openings 73 and thence into the reservoir 50. During this operation air will escape upwardly 125 130

4

through the apertures 72 into the cup portion and thence to the external atmosphere. After the reservoir has been partly or entirely filled the cap 74 is replaced. As heretofore stated the tapered end 71 of the spindle normally closes the aperture 52. By now rotating the cup 69 the spindle will be partly unscrewed within the shank 46 so as to move the tapered end 71 slightly away from its seat. This rotation can be limited by the spring pin 67 coming against the projecting end of the set screw 66 or, if it is desired to provide a very small opening for the escape of ink from the reservoir, the rotation of the cup 69 can be stopped before the spring pin 67 reaches the stop or set screw 66. In that event the frictional engagement of the spring pin 67 with the grooved or knurled surface of the nut or collar 65 will be sufficient to hold the parts against relative movement. When the aperture 52 is opened the ink will not flow therethrough because air will not be admitted to displace it. When the user is ready to operate the machine he depresses the plunger 79. This will allow air to flow downwardly into the reservoir 50 and an amount of ink equal to the amount of air admitted will thus flow through the opening 72 into the spreading or distributing chamber 51 and thence through the apertures 55 to the bristles of the brush. When a sufficient amount of ink has been supplied to the bristles the plunger 79 is released and will close under the action of spring 82. By placing the machine on the surface to be stenciled the stenciling operation is effected simply by thrusting the device forwardly. This will cause the rear drum to roll upon the rear portion of the stencil while the front portion of the stencil will unroll from the front drum. As this operation is taking place spring 44 is placed under tension and motion is transmitted through the train of gears from the drum to the brush with the result that said brush will be rotated at a high speed over the upper surface of the stencil and will spread the ink thereover thoroughly. Spring 58 will hold the brush pressed tightly against the stencil. During the beginning of this forward movement of the machine the spring pressed key 24 is located against one side of the lug or stop 21 and as the machine travels forward this key is movably engaged by the inclined surface of the cam 20. During the second half of the forward movement of the machine cam 20 rotates until shoulder 20' comes against key 24. At this time a slight further rotation of the drums is permitted by reason of the fact that the groove 22 is wider than the thickness of key 24. Thus a complete rotation of the cam is permitted. As soon as the machine is thus brought to a stop it can be lifted off of the surface being stenciled and immedi-

ately thereafter the tensioned spring 44 will reverse the rotation of the drum so that the movement of the key 24 on the cam 20 will be reversed. Consequently during the completion of this reverse rotation of the parts 70 key 24 will again travel upwardly along the inclined face of the cam until it ultimately comes against the stop or lug 21. These cooperating parts obviously act as a brake for gradually stopping the mechanism so that there will be no injury resulting from pounding of the parts which would otherwise occur. As the parts are promptly reset as soon as the machine is lifted off of the stenciled surface said machine is at once ready to be again operated as described and when the stencil print produced on a surface shows signs of fading out the operator can as necessary, depress the plunger 79 so that a new supply of ink 80 will be admitted to the brush bristles.

In view of the ratchet connection between the gears and the brush, said brush will only be revolved during the forward or stenciling operation. When the stencil is 90 reset after the completion of each stenciling operation the brush will remain stationary and the cooperating members 89 and 90 will slip relative to each other.

Attention is called to the fact that practically all of the mechanism of the present invention is carried by the skeleton frame. Thus the parts can be assembled readily after which the housing can be placed over the frame and fastened thereto by the several means extending from the skeleton frame and through the walls of the housing.

For the purpose of taking up wear and at the same time indicating the correct positions of the ends of the stencil when applied to the drum, a wear plate 105, which is arcuate in cross section, may be secured within each groove or depression 16, 38 in the drums. Each of these plates is provided, along one edge, with an outstanding stop flange 106. 100 Thus after the gripping roll has been rotated to releasing position, as shown in Figure 11, the end of a stencil can be inserted between the roll and the plate 105 until it comes against flange 106 after which the gripping roll can be rotated to clamping position. For the purpose of limiting the rotation of the gripping roll to releasing position, a stud 107 may be extended laterally from one head of each drum. Thus when either of the gripping rolls is rotated to releasing position the arm 19 thereon will come against the stop lug 107 when the roll is in full releasing position. At this time it is essential that some guide means be employed for centering the stencil while it is being inserted into engagement with the plate 105. For this purpose there are provided guide washers 108 upon the pins 18, 41 at the ends of the gripping rolls 17, 40 110 115 120 125 130

and these washers will project inwardly toward the plates 105 when the gripping rolls are in their releasing positions.

The nut or collar 65 constitutes a means for limiting the sliding movement of the tubular shank 46 within its supporting means. In other words spring 58, which normally exerts a downward thrust upon the shoulder 57, tends to hold the nut or collar 65 normally pressed against the bushing 61. In use, however, the brush 54 is thrust upwardly by the pressure against the stencil but as the brush wears away the spring 58 will compensate for the wear. After a certain amount of wear upon the brush has occurred, the nut or collar 65 can be adjusted longitudinally along the shank 46 to allow further downward movement of the shank and brush. Thus it is possible to use the brush even though the bristles are worn down close to the plate 53. The collar or nut 65 will of course prevent excessive movement downwardly of the brush under the action of the spring 58.

Ball bearings can be provided wherever deemed essential and in the present instance a ball bearing 109 has been shown between the bushing 60 and the gear 59.

What is claimed is:

1. A stenciling machine including a portable structure, drums journaled therein for supporting the same, each drum having a longitudinal depression, eccentrically mounted gripping means within the depressions for attaching the ends of a stencil thereto, a horizontally movable brush within the structure and between the drums, and drive connections between the drums and the brush, said connections including means for moving the brush in one direction only during the back and forth rotation of the drums.

2. A stenciling machine including a portable structure, spaced drums journaled therein for supporting the structure, eccentrically mounted gripping means for attaching the ends of a stencil to the respective drums, a brush mounted for horizontal movement between the drums, a driving connection between the drums and the brush for moving the brush in one direction only during the back and forth rotation of the drums, and yielding means within one of the drums for holding both of the drums normally in predetermined positions.

3. In a stenciling machine a portable structure, spaced drums journaled therein for supporting the same, a brush mounted for horizontal movement between the drums, a driving connection between the drums and the brush, means within one of the drums for normally holding the drums yieldingly in predetermined positions, and means within the other drum for automatically retarding the movement of the drums

during the completion of the rotation thereof in one direction.

4. In a stenciling machine a portable structure, spaced drums journaled therein for supporting the same, a brush between the drums, a driving connection between the brush and the drums, yielding means connected to one of the drums for automatically returning the drums to their normal positions, and means carried by and cooperating with the other drum for automatically retarding the movement of the drums during the completion of the rotation of the drums under the action of said yielding means.

5. In a stenciling machine a portable structure, stencil carrying drums journaled therein for supporting the same, a brush movably mounted between the drums, a driving connection between the drums and the brush, yielding means connected to one of the drums for returning the drums to their normal positions after being rotated out of normal positions and released, and cooperating means carried by the other drum and adjacent said drum respectively for retarding the rotation of the drums during the completion of their rotation to normal position.

6. In a stenciling machine a portable structure, spaced drums mounted for rotation therein for engagement by a stencil and for supporting the structure, a brush between the drums, a driving connection between the drums and the brush, a shaft supporting one of the drums, a cam having an inclined surface and rotatable with the drum, a stop projection upon the peak portion of the cam, and spring pressed means carried by the shaft for slidably engagement by the inclined face of the cam to retard the rotation of the drum during the latter portion of the movement thereof in one direction.

7. In a stenciling machine a portable structure, spaced drums mounted for rotation therein for engagement by a stencil and for supporting the structure, a brush between the drums, a driving connection between the drums and the brush, a shaft supporting one of the drums, a cam having an inclined surface and rotatable with said drum, a stop projection upon the peak portion of the cam, and spring pressed means carried by the shaft for slidably engagement by the inclined face of the cam to retard the rotation of the drum during the latter portion of the movement thereof in one direction, there being a lost motion connection between the spring pressed means and the shaft to permit limited rotation of the drum subsequent to engagement of the stop device with the spring pressed means.

8. In a stenciling machine a portable structure, spaced stencil engaging drums journaled therein for supporting the struc-

ture, a brush movably mounted between the drums, a driving connection between the drums and the brush, a reservoir and a distributing compartment in superposed relation within the brush, said distributing compartment having outlets opening into the spaces between the bristles of the brush, a valve normally closing communication between the reservoir and the distributing compartment, and means outside of the structure and under the control of the operator for admitting air to the reservoir and releasing marking fluid from the reservoir to the distributing chamber when the valve is open.

9. A stenciling machine including a portable structure, spaced drums journaled therein for supporting the structure, a brush mounted for movement between the drums, a driving connection between the brush and the drums, a reservoir and a distributing chamber carried by the brush in superposed relation, said distributing chamber having outlet openings to the bristles of the brush, a valve normally closing communication between the reservoir and the distributing chamber, a filling cup rotatable with the valve and constituting means for opening and closing the valve, there being an air passage through the cup and valve and opening into the reservoir, and means under the control of the operator for regulating the flow of air through the valve to the reservoir.

10. In a stenciling machine the combination with a portable structure, of stencil engaging drums journaled therein for supporting the same, a brush movably mounted between the drums, a driving connection between the drums and the brush, a reservoir for marking fluid within the brush, a distributing chamber having outlets to the bristles of the brush, a valve normally closing communication between the bottom of the reservoir and a distributing chamber, a filling cup connected to and opening into the valve, said cup being located outside of the structure and rotatable to open and close the valve, means for controlling the rotation of the filling cup, there being an air passage through the valve and the cup opening into the reservoir, and means under the control of the operator for regulating the flow of air to the reservoir and consequent flow of marking fluid from the reservoir to the distributing chamber.

11. In a stenciling machine a portable structure, stencil engaging drums journaled therein for supporting the structure, a brush movably mounted between the drums, a driving connection between the drums and the brush, a reservoir carried by the brush, a distributing chamber thereunder having apertures for directing marking fluid to the bristles of the brush, a valve controlled from

a point outside of the structure for opening and closing communication between the reservoir and the distributing chamber, and means under control of the operator and outside of the structure for opening and closing communication between the reservoir and the external atmosphere to control the flow of marking fluid from the reservoir to the distributing chamber.

12. In a stenciling machine a portable structure, stencil engaging drums journaled therein for supporting the same, a brush mounted for movement between the drums, a driving connection between the drums and the brush, a normally sealed reservoir for marking fluid, a valve for controlling communication between the bottom of the reservoir and the bristles of the brush, and means outside of the structure and under the control of the operator for controlling the admission of air to the reservoir and, consequently, the delivery of fluid from the reservoir.

13. A stenciling machine comprising a portable structure, drums rotatably mounted in the opposite ends of said structure movably supporting the same, a rotary horizontally positioned brush supported within the structure between said drums, a reservoir carried by the brush having an outlet communicable with the bristles thereof, and means connected to said reservoir adapted to permit the filling of said reservoir and to control and regulate the flow of marking fluid from the same onto said bristles, said means including a tubular spindle normally opening into the reservoir, a valve at one end of the spindle normally closing the outlet, and a yieldingly held valve normally closing the inlet end of the tubular spindle, said yieldingly held valve being depressible to admit atmospheric pressure to the spindle and to the reservoir.

14. A stenciling machine comprising a portable structure, spaced drums mounted in said structure movably supporting the same, a rotary horizontally positioned brush supported within the structure between said drums, a reservoir communicable with the brush bristles having an air inlet and a fluid outlet, valve means within said reservoir for controlling and regulating the flow of fluid therefrom onto said bristles, means under the control of the operator for regulating the admission of air to the reservoir thereby to control the flow of fluid from the reservoir to the bristles and laterally movable means for limiting the extent of rotary movement of said drums.

15. A stenciling machine comprising a portable structure, drums rotatably mounted in the opposite ends of said structure movably supporting the same, laterally movable means for controlling the extent of rotary motion of said drums, means connected to one

of the drums for returning the drums to their initial and normal positions, a rotary horizontally positioned brush supported within the structure between said drums, a reservoir carried by the brush communicable with the bristles thereof, and valve means for controlling and regulating the flow of marking fluid from the reservoir to said brush bristles.

16. A stenciling machine comprising a portable structure, drums rotatably mounted in the opposite ends of said structure movably supporting the same, means operatively connected with one of said drums for limiting the extent of rotary movement of the same, other means connected to the remaining drum for causing return of the drums to their initial and normal positions upon release of their peripheral portions from pressure upon a surface, a rotary horizontally positioned brush yieldably and slidably supported within the structure between said drums, a reservoir carried by the brush communicable with the bristles thereof, and manually operable valve means adapted to be operated from a point externally of the structure for controlling and regulating the flow of marking fluid from the reservoir onto said bristles.

17. A stenciling machine comprising a portable structure, drums rotatably mounted in the opposite ends thereof movably supporting the same, a rotary horizontally positioned brush supported within the structure between said drums, means connected to said drums for transmitting rotary motion to said brush in one direction, a reservoir carried by the brush communicable with the bristles thereof, and manually operable valve means adapted to be operated from a point externally of the structure for controlling and regulating the flow of marking fluid from the reservoir onto said bristles.

18. A stenciling machine comprising a portable structure, drums rotatably mounted in the opposite ends thereof movably supporting the same, means operatively connected to one of said drums for limiting the extent of its rotary motion, other means connected to the remaining drum for causing the return of both drums to normal positions subsequently to disengagement of the same from a surface, a rotary horizontally positioned brush yieldably and slidably supported within the structure between said drums, a reservoir carried by the brush communicable with the bristles thereof, and combined filling and manually operable valve means connected to said reservoir for permitting the filling of the reservoir with marking fluid and for controlling and regulating the flow of marking fluid from such reservoir onto said bristles.

19. A stenciling machine comprising a portable structure, drums rotatably mounted in the opposite ends of said structure mov-

ably supporting the same, a horizontally movable brush supported within the structure between said drums, a reservoir carried by the brush having an air inlet and a fluid outlet, said outlet being communicable with the bristles of the brush, and manually operable valve means for controlling the admission of air to the reservoir to displace a predetermined quantity of marking fluid from the reservoir onto said bristles.

20. A stenciling machine comprising a portable structure, drums rotatably mounted in the opposite ends of said structure movably supporting the same, a horizontally movable brush positioned within the structure between said drums, a reservoir carried by the brush having an air inlet and a fluid outlet, said outlet being communicable with the bristles, and means manually operable from a point exteriorly of the reservoir for controlling the admission of air to the reservoir to displace a predetermined quantity of marking fluid onto said bristles.

21. A stenciling machine comprising a portable structure, drums rotatably mounted in the opposite ends of said structure movably supporting the same, a horizontally positioned movable brush within the structure between said drums, a reservoir carried by the brush having an air inlet and a fluid outlet, said outlet being communicable with the bristles thereof, a valve within said reservoir for regulating the outlet, and means, manually operable from a point exteriorly of the same and of said structure, for controlling the admission of air to the reservoir to displace a predetermined quantity of marking fluid from the reservoir onto said bristles.

22. A stenciling machine comprising a portable structure, drums rotatably mounted therein and movably supporting the same, a brush movable horizontally between the drums, a driving connection between the drums and the brush, yielding means for normally pressing the brush in one direction, a reservoir communicable with the brush bristles, and valve means for controlling and regulating the flow of fluid from the reservoir to the bristles.

23. A stenciling machine comprising a portable structure, drums rotatably mounted therein and movably supporting the same, a brush movable horizontally between the drum, a driving connection between the drums and the brush, yielding means for normally pressing the brush in one direction, a reservoir communicable with the brush bristles, a valve for opening and closing communication between the reservoir and the spaces between the brush bristles, and means for controlling the flow of air to the reservoir to displace fluid therein and control the flow of fluid from the reservoir.

24. A stenciling machine including a por-

table structure, spaced drums mounted there-in for supporting the same, a yieldingly supported brush mounted for movement be-tween the drums, a reservoir, means for open-ing and closing communication between the reservoir and the bristles of the brush, means outside of the structure and under the control of the operator for admitting air to

and cutting it off from the reservoir, thereby to control displacement of fluid from the reservoir to the bristles, and a housing detachably mounted on the structure.

In testimony that I claim the foregoing as my own, I have hereto affixed my signature.

JOHN WALKER INGLESBY.
